UNITED STATES PATENT OFFICE.

JACKSON D. COMSTOCK, OF CHESTER, WEST VIRGINIA.

DESIGN FOR AN AUTOMOBILE TIRE.

Application filed June 11, 1923. Serial No. 6,465. Term of patent 14 years.

To all whom it may concern:

Be it known that I, JACKSON D. COMSTOCK, a citizen of the United States, residing at Chester, in the county of Hancock and State of West Virginia, have invented a new, original, and ornamental Design for an Automobile Tire, of which the following is a specification, reference being had to the accompanying drawings, forming a part hereof.

Fig. 1 is a side elevation of a segment of an automobile tire embodying my invention; Fig. 2 is a cross section through the tire, showing also some of the side wall in perspective.

I claim:

The ornamental design for an automobile tire as shown.

JACKSON D. COMSTOCK.
